UNITED STATES PATENT OFFICE.

JAMES H. GRAHAM AND MAHLON S. FOLEY, OF TORRINGTON, CONNECTICUT,
ASSIGNORS TO THE TORRINGTON COMPANY, OF TORRINGTON, CONNECTICUT, A CORPORATION OF CONNECTICUT.

DIE FOR MAKING SPOKE-NIPPLES.

1,395,181.

Specification of Letters Patent.

Patented Oct. 25, 1921.

Application filed October 20, 1917. Serial No. 197,643.

To all whom it may concern:

Be it known that we, JAMES H. GRAHAM and MAHLON S. FOLEY, citizens of the United States, residing at Torrington, in the county 5 of Litchfield, State of Connecticut, have invented certain new and useful Improvements in Dies for Making Spoke-Nipples, of which the following is a description, reference being had to the accompanying drawing, and 10 to the figures of reference marked thereon.

The invention relates to improvements in dies for making spoke nipples.

The object of the invention is to provide a die and plunger in which a round straight 15 bar or slug of a determined length can be formed into a nipple having a kerfed head, a round portion and a rectangular outer portion, by endwise movement of a plunger against one end forcing it into the die.

20 Another object of the invention is to provide a cheap and effective die which, by a single or a continuous operation, will form a strong and durable nipple and having certain combination of parts and details of 25 construction and operation hereinafter more fully set forth.

In the accompanying drawings,—

Figure 1 is a vertical longitudinal sectional view of one form of die, in which a 30 nipple of the character shown in our application filed October 3, 1917, Serial Number 194,539 is formed;

Fig. 2 is an end view of Fig. 1 with a portion of the die removed;

35 Fig. 3 is a vertical longitudinal sectional view of a further modified form of die;

Fig. 4 is an end view of Fig. 3 with a portion of the die removed;

Fig. 5 is a side elevation of a blank or 40 slug from which a nipple is formed in our improved die, and

Fig. 6 is a side elevation of the complete nipple made in our improved die.

Referring now to the drawings, the dies 45 are in the form of a composite steel block, having a bore therethrough, and said block is adapted to be held in any desired manner in the die assembly as well known in the art. After the die has been assembled, the blank 50 such as shown in Fig. 5, is inserted in the die, one end resting against the usual stop

which may be inserted through a bore 13 of Figs. 1 and 3 so that one end of the blank will rest firmly thereagainst. A heading die is then brought against the projecting end of 55 the blank 11 to cause the metal of the blank to flow and form a nipple corresponding to the inner contour of the die. If desired, this heading die may be provided with the usual depressions on each side of a solid web, 60 to form a kerf, all of which is well known in the prior art.

Inasmuch as the present invention resides particularly in the form of the composite die, with the registering bores of specific 65 inner contour, only a description of this die will be given. The steel block is preferably made of three pieces, including a main body portion 12 having a small round bore 13 through a portion of it, and an enlarged 70 round recess 14 surrounding the bore at one end. A second portion or back 15 fits within the recess and is provided with a rectangular bore 15' therethrough, the ends of which are beveled as indicated at 16. Resting against the body portion is a third part 75 17 of the same diameter, having a round bore 18 therethrough, which has its outer end slightly enlarged and beveled as indicated at 19 to form a head, as heretofore described. 80 The several parts are placed in the die assembly and held in the position shown in Fig. 1.

In Fig. 3, instead of having a back made of a single piece as shown in Fig. 1, it is 85 made of two pieces 20 and 21 as clearly shown in Fig. 4. In both instances, the operation of the plunger is exactly as that described above.

Having thus described our invention, what 90 we claim as new and desire to secure by Letters Patent, is:—

1. A die of the character described comprising a body portion having a bore and an enlarged recess, a back in said recess having 95 a registering bore formed with flat walls terminating in beveled ends, and a member resting against the body portion and having a round bore registering with the angular bore and having a beveled outer end, all of 100 the parts held in their correlated position by a die assembly.

2. A die of the character described comprising a body portion having a bore and an enlarged recess surrounding the bore, a back in said recess formed of two parts and having angular recesses forming an angular bore with beveled ends and a member resting against the body portion over the back and having a round bore registering with the angular bore and having a beveled outer

end all of the parts held in their correlated position by a die assembly.

In testimony whereof we affix our signatures in the presence of two witnesses.

JAMES H. GRAHAM.
MAHLON S. FOLEY.
